WATER HOSE CABINET FOR FILLING STATIONS

Julius H. Holmgreen, San Antonio, Tex.

Application January 11, 1932. Serial No. 586,044

6 Claims. (Cl. 299—77)

This invention relates to water hose cabinets adapted to be used at filling stations and particularly to radiator filling equipment and to means for preventing freezing of the liquid within the cabinet.

An object of this invention is to provide an insulated cabinet having heating means mounted therein which would prevent freezing within the cabinet and especially one that is adaptable to be used during very cold weather and in cold climates.

Another object is to provide a mechanical arrangement for releasing and retracting the hose and one that will afford protection to the hose at all times when not in use.

Referring to the accompanying drawing, which is made a part hereof and on which similar reference characters indicate similar parts,

Figure 1 is a view in elevation showing the entire cabinet, partly in section,

Figure 2, a sectional view on line 2—2 of Figure 1,

Figure 3, a sectional view on line 3—3 of Fig. 1, and

Figure 4, a sectional view of the nozzle and closing cover.

In the drawing reference character 10 indicates the main body portion of the cabinet which is formed of spaced members 11 and 12 of any suitable material and with a suitable insulating material 13 filling the space between the members. The main body 10 is secured to a base 14 in any suitable manner. The base 14 is formed of a pair of spaced integral portions 52 and 53, thus providing a housing as clearly shown in Figure 1, and for a purpose which will later be described. A removable plate 65 is provided on the base for access to the base for making necessary repairs and replacements. The portion 53 is provided with a plurality of openings 54 in communication with the interior of the body portion 10. An opening 55 is provided in the portion 52 for draining any waste liquid from the base 14 which might be caused by leaks and also serves as an air inlet to the housing and the cabinet. The portion 52 is also provided with a flange 15 having a plurality of openings 16 therethrough by means of which the cabinet may be anchored or secured in upright position. Any suitable means such as bolts, lag screws or the like may be used for this purpose.

A collar 17 is secured to the top of the body of the cabinet and is provided with an opening 18 through which a hose 19 may be withdrawn and returned to the cabinet. A cap or cover 20 is mounted on the collar 17 completing the cabinet.

A pulley housing 21 is mounted in the upper portion of the cabinet and is supported by the arms 22 resting in the slots 23 formed in the in-

terior of the collar 17 and so located that the arms 22 are at right angles to the opening 18. A pair of pulley wheels 24 are rotatably mounted on a shaft 25 fixed in the housing 21. Another pulley housing 26 having a shaft 27 fixed therein is located beneath and slightly displaced to one side of the upper housing 21 within the cabinet when the apparatus is assembled as shown in Figures 2 and 3. A pair of pulley wheels 28 similar to pulley wheels 24 is rotatably mounted on the shaft 27. The pulley wheels 24 and 28 are mounted on ball-bearing 29 to insure free operation on their respective shafts. The lower portion 30 having an opening 31 in the bottom thereof through which a chain 56 may be secured by a pin 57 or any other suitable means. The chain 56 has a weight 58 secured at its lower end and which normally seats in the center of the base against the supporting surface on which the cabinet is erected. The depending portion 30 is also provided with a flange 32 which prevents the housing 26 from scraping or rubbing the interior of the cabinet as the housing 26 is raised or lowered in the cabinet.

An inlet pipe 33 is connected through an opening 34 in the base 14 and extends upwardly to the top of the cabinet and is connected by suitable means to the hose 19. The opening 34 is provided with a drain plug 59. The hose 19 is wound over the upper and lower pulley wheels as clearly shown in Figure 1, the free end of which is connected to a coupling 35. A nozzle 36 is in turn secured to the coupling 35.

The opening 18 in the collar 17 is so arranged that a nozzle housing 37 projects into the opening 18 and is held in position by a screw 38 threaded into a lug 50 on the cap 20. The housing 37 is provided with a hinged cover 39 which may be locked by any suitable means not shown through the openings 40 and 41 in the housing and the hinged cover respectively. The housing 37 forms a seat for the nozzle 36 and which may be cushioned by a gasket 42 of any suitable material. The nozzle 36 is provided with a body portion 43 having a flange 44 which seats and is cushioned against the gasket 42 when the hose is in place in the cabinet. The nozzle is operated by a lever 51 having a pin 45 eccentrically located operating in a collar 46. A stem 47 is connected to the collar 46 and has at the rear end a rubber washer 48 which rests against the inlet end of the body portion 43 of the nozzle. Any movement of the lever to the right or left will throw the ball washer off its seat and allow the liquid to flow from the outlet 49. It will be noted that the upper pulley wheels are so located that the projecting end of the nozzle extends slightly downwardly. In this position the hose may be pulled from and returned to the cabinet with least wear

and if any leaks should occur the drip will be outside the cabinet.

An electric heating element 60 is secured within the housing formed by the base 14 and is supported by a bracket or socket 61 secured thereto and well above the level of the floor to such a point that any water that may stand therein will not short circuit the electrical equipment. Wires 62 are embedded in the insulating material 13 connecting the heating element to a socket or plug 63 near the top of the cabinet and to which the outside connections may be made. A thermostat 64 may be connected and mounted within the cabinet for controlling the temperature.

An electrical heating arrangement has been shown for the purpose of description, but it is possible to use a gas or oil heating apparatus therefore it is not necessary to limit the arrangement to any specific system of producing and controlling heat.

The operation of the device is very simple. To use the device one merely grasps the nozzle and pulls out a length of hose necessary to reach the radiator or vessel which is desired to be filled. The lower pulley housing or block which hangs in the cabinet will rise as the hose is pulled from the cabinet carrying the chain and weight attached thereto to some distance above the floor level thus adding considerable weight to the lower block and giving power to automatically retract the long hose filled with water when released. Upon releasing the nozzle the block travels some distance downwardly, the weight strikes the floor thus reducing the pull, as the block continues the chain likewise strikes the floor causing the block to slow up and lessen the shock on the hose and fixtures.

The heating element being located at the bottom or near the bottom of the casing warms the air which enters the opening 55 and which passes upwardly through the openings 54 thereby preventing freezing of the liquid in the cabinet. During warm weather the heating apparatus may be dispensed with and the apparatus used without any additional changes or expense.

It will also be noticed that the base is so constructed that it affords complete protection to the heating element and prevents damage to it from any of the moving parts of the equipment.

It may be seen from the above described structure that a hose cabinet results which not only prevents damage or inconvenience due to freezing of liquid in the cabinet but also serves as a safe and convenient storage for such equipment when not in use.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

1. A hose cabinet adapted for dispensing water at filling stations comprising a casing, a feed pipe extending upward therethrough to the top, a hose connected to said pipe, a nozzle on the other end of said hose and extending outward of the casing, pulleys mounted in the top of said casing for supporting said hose, lower pulleys supported by the loops of said hose to keep them

taut, a chain attached to said lower pulleys and a compensating weight means carried by said chain for counterbalancing the weight of said hose within said casing, substantially as set forth.

2. A hose cabinet adapted for dispensing water at filling stations comprising a vertical casing, a water feed pipe in said casing, a coiled hose having one end connected to said pipe and a nozzle on the other end extending outside of said casing, stationary pulleys mounted adjacent the top of said casing and supporting said hose, floating pulleys carried by the loops in said hose and a compensating weight means for counterbalancing said hose attached to said floating pulleys, said weight comprising a plurality of elements so arranged as to add their weight gradually to said floating pulleys as the floating pulleys are raised, substantially as set forth.

3. A hose cabinet adapted for dispensing water at filling stations comprising a vertical casing, a water feed pipe extending up through said casing, a coiled hose within said casing having one end connected to the upper end of said pipe and a nozzle on the other end, stationary pulleys mounted adjacent the top of said casing and supporting said hose, floating pulleys carried by the coils of said hose and a compensating weight means carried by said floating pulley, said weight means adapted to add weight as the floating pulleys raise and diminish in weight as the floating pulleys lower, substantially as set forth.

4. In a hose cabinet comprising a vertical casing, a feed pipe extending upward therethrough, a coiled hose normally within the casing having one end connected to said pipe and a nozzle on the other end, stationary pulleys in the top of said casing for supporting said hose, floating pulleys carried by the coils of said hose, a compensating weight means attached to said floating pulleys, said means comprising a heavy chain having its upper end secured to said floating pulleys and a heavy weight on the lower end, said weight and chain adapted to rest on the floor when the hose is all in the cabinet and to be successively lifted as the hose is drawn out of said casing, substantially as set forth.

5. A water dispensing device comprising a cabinet having a plurality of fixed pulleys supported in its upper portion, a hose wound about said pulleys, a second group of pulleys supported on said hose, a weight, a flexible element connecting said weight to said second group of pulleys for gradually applying weight to said last named pulleys as these pulleys are raised, a water pipe entering said cabinet and connected to one end of said hose, a heating element positioned in the base of said cabinet to prevent freezing of the water in said hose, and a thermostat positioned in said cabinet in control of said heating element, substantially as set forth.

6. A device for dispensing water comprising a cabinet having a group of pulleys supported in its upper portion, a hose wound about said pulleys, a second group of pulleys supported on said hose, a water conduit extending into said cabinet and attached to the said hose, a base supporting said cabinet, said base having a housing therein, a heating element positioned in the housing, and a plurality of perforations forming communication between the housing and the interior of the cabinet to permit circulation of warmed air up through the cabinet, substantially as set forth.

JULIUS H. HOLMGREEN.
